ROTARY MUFFLE FURNACE

Paul Jordan, Frankfort-on-the-Main, Germany,
assignor to American Lurgi Corporation, New
York, N. Y., a corporation of New York

Application June 9, 1937, Serial No. 147,332
In Germany June 10, 1936

15 Claims. (Cl. 263—34)

This invention relates to rotary muffle furnaces of the type consisting of a muffle to receive the material to be treated and a shell carrying the muffle, the furnace being heated by means of fire ducts disposed between the muffle and the shell.

The difficulties attending the construction and operation of such furnaces lie in the securing of the muffle to the outer shell, and the calking of the internal muffle against the fire ducts, especially in cases where the muffle is constructed of a plurality of parts. Revolving muffles having their walls sub-divided both longitudinally and transversely to the axis of the muffle, or longitudinally thereto only, have already been constructed with the longitudinal joints of the muffle supported on bricks projecting from the masonry of the furnace shell. These bricks, usually wedge-shaped, have also been provided with a recess for the reception of a lug formed from projections provided on the longitudinal edges of each muffle segment.

While muffle furnaces so designed are suitable for calcination, they are not suitable for the melting of material containing metal, since the joints could not heretofore be made tight against liquid metal.

The lack of tightness is due to the differing amounts of axial and circumferential expansion occurring in the individual structural parts. When the furnace is heated up, the masonry in the iron shell expands more than the muffle inside the furnace. The bricks projecting inward from the furnace lining, which are intended to hold the muffle in position and at the same time to calk the joints where the muffle segments abut together by their firm hold on the projections on the longitudinal edges of the muffle sections, recede more from the joints of the muffle segments, under heat expansion, than the muffle approaches under the expansion of its own bricks. Thus they are not capable of holding the projections of the muffle sections tightly together at high temperatures.

The main object of the present invention is to overcome this disadvantage, and this is accomplished by connecting the internal muffle, whether composed of a plurality of segmental parts or of one or more mutually adjacent tubular sections, directly with the shell by yielding parts, preferably in such wise that the muffle is brought into bearing with counter-bearing elements provided on the inner side of the furnace shell, by means of the yielding parts, which exert a thrust or a pull on the muffle.

For example, there may be disposed in the

masonry of the furnace shell two or more rows of bricks projecting into the interior of the furnace. On the side opposite the rows of bricks, spring plungers or similar pressure-exerting means are provided, preferably likewise in multiple-rowed arrangement, which act on the muffle and press it against the rows of bricks. The spring plungers are yielding, so that they will always hold the muffle sufficiently firmly to preclude any displacement relative to the shell, but under heavy loading they can yield, preventing destruction of the muffle by excessive pressure. Or, the plungers or other yielding holding means are pressed against the muffle by springs which act between the plungers and the furnace shell.

In the drawings—

Figure 1 is a section through a muffle furnace according to the preferred embodiment of the present invention, taken along the line A—B of Fig. 2;

Figure 2 is a longitudinal section through the muffle furnace;

Figure 3 is a cross-section showing details of the brick arrangement;

Figure 4 is a longitudinal section through the same;

Figure 5 is a plan view of the same;

Figure 6 is a perspective view of a piece cut from the muffle furnace;

Figure 7 is a section through Figure 8 showing a modified brick arrangement;

Figure 8 is a plan view of Figure 7;

Figure 9 is a modification of Figure 2; and

Figure 10 is an enlarged detail of a portion of Figures 2 and 9.

The muffle in this example is sub-divided in cross-section into five segments, as shown in Figure 1. The muffle may also be sub-divided perpendicular to the axis of rotation, so that two or more tubular sections are formed, each of which is composed of five segments 1, constructed for example of silicon carbide. The inner lining 2 of the iron furnace shell 2a is constructed of fire clay or the like, and is provided with five ribs made of preferably wedge-shaped bricks 3, 4, and 5.

Between the shell 2a and the lining 2 there is also preferably provided a heat-retaining layer 2b, constructed for example of insulating bricks. The bricks 3 are preferably equipped with shoes 3a, of silicon carbide for example, placed between the muffle and the bricks, to afford the muffle a broader bearing surface. To guard against displacement of the shoes on the bricks, the contact surfaces preferably have a dovetail form.

The bricks 4 and 5 are preferably held in the masonry, as shown in Figures 3, 4 and 5, by disposing bricks 6 between the bricks 4 and 5 in each row; the bricks 6 are preferably also wedge-shaped. However, the bricks 6 do not completely fill the space between bricks 4 and 5 in each row, but leave spaces 7 free between them. The bricks 4 and 5 are of such shape that, in each row, the mutually confronting lateral surfaces of the bricks 4 and 5 are parallel to one another for one-half of the height of the brick.

In the space bounded by the parallel surfaces rise the projections 8a of the shoes 8. The shoes 8 are pressed against the internal muffle by the plungers 9, which are urged thereagainst by the springs 10, the pressure of which may be adjusted by means of nuts or screw caps 10a. The shoes 3a of the bricks 3 form the counter-bearings for the muffle, and the springs 10 insure that the muffle is always pressed against these counter-bearings.

The fire ducts 18 are formed by pairs of ribs constituted of bricks 4 and 5, or 3 as the case may be, and by the muffle wall and the lining of the drum shell. The plungers can be further protected against overheating by a suitably resistant loose block 11. Instead of forming the ribs with the bricks 4 and 5, it is of course possible to make them of undivided bricks 33 provided with suitable perforation or molded-in opening 34 as shown in Figures 7 and 8, so that instead of pairs of bricks 4 and 5 single bricks are used. The number of segments and consequently of bearing rows and of fire ducts can of course be varied within wide limits.

The muffle according to the present invention is distinguished by other advantages in addition to the reliable fastening to the furnace shell. It has the further considerable advantage that it can be made of a large number of segments or other shaped pieces, and that nevertheless the joints, particularly those running parallel to the axis of rotation of the muffle, are dependably tight against molten materials. In order to insure the tightness of the joints circumferential to the muffle, additional special measures can be applied if necessary. This also can often be dispensed with, for example if the muffle is not subdivided longitudinally, or if fusion takes place in only one section of the muffle and the molten material does not reach the circumferential joints.

If sufficiently long muffle segments are used, it is possible in many cases, by suitably inclining the furnace, to avoid having any circumferential joint touched by liquid metal, that is to say, a metal bath is formed only in the lowest section of the muffle.

But if the zone of fusion has to be greater than the possible or advantageous structural length of a muffle section, and if the calking of the circumferential joints against the fire ducts offers special difficulties, it is possible according to the invention, in order to prevent liquid metal from penetrating into the fire ducts, to use a special form of muffle segment which confines any passage of metal to those points of the circumferential joints which are located over one of the ribs formed by the bricks 3 or 4 and 5. For this purpose the sectional pieces of the muffle wall are made, for example trough-shaped.

As shown in Figure 6, the trough-shape can be obtained by equipping the sections 12 on their circumferentially running edges with inwardly extending projections or rims 14. In this man-

ner there are formed a number of compartments corresponding to the number of consecutive sections in the axial direction. The liquid metal present in one of the compartments of the furnace can flow into the adjoining compartment only through the matched openings 13 in the abutting rims 14 of two sections or segments 12, and so long as no opening is lower than the surface of the bath it will be confined to its own compartment of the muffle.

The height of the flange-like rims 14 and the depth of the cut-outs 13 can be determined to suit the kind and quantity of metal in the compartment. The muffle segments 12 can be further reinforced with internal or external stiffeners 15, which when internal serve also as turning devices and when external improve the heat absorption.

When materials or mixtures are treated which are not required to be protected from contact with fire gases except at high temperatures, the furnace can also be so constructed as shown in Figure 2, so as to have one part, say the lower part in an inclined furnace, serve as muffle furnace, and the other part as direct-heated or combination-heated furnace. In such case the heating gases may be led by means of pipes 17, from the fire ducts 18 of the muffle into the part of the inclined furnace which serves as preheating or drying section for the material to be treated. The pipes 17 may be of heat and corrosion-resistant metal or refractory material, and when passing through the lowest point still project beyond the level of the charge. With this arrangement direct transmission of heat from the heating gas to the material treated is accomplished.

The fire ducts 18 may end over the highest pipe 17 as shown in Figure 9, so that the removal of the gases takes place through the furnace and the upper furnace-head. But as shown in Figure 2 it is also in many cases advantageous to pass one part of the furnace gases through the upper part of the furnace and to use another part for the external heating of the whole upper portion of the apparatus. The internal and external heating can also be effected in this case by other heating media than those serving for the heating of the muffle.

The length of the indirectly and directly heated zones of the furnace may differ greatly and will be adapted to the type of process being carried on. If for example it is desired to reduce material containing iron oxide to iron sponge or powder with the aid of gases, which are brought in, for example through the conduit or pipe 40 through the lower furnace-head and through the opening 21, it will be advantageous to have the indirectly heated zone begin at the point where the reduction from Fe_2O_3 to FeO is nearly or entirely completed. The reduction from FeO to Fe then follows in the indirectly heated part of the furnace, possibly at higher temperature. The gases of reduction leaving the indirectly heated zone through the pipe section 17 shown in Figure 9 are burned in the directly heated zone, mainly in the upper part thereof, air being supplied, preferably in stages, through openings 36 distributed along the length, and advantageously also about the circumference, of the furnace shell, and when so burned heat the charge to the necessary temperature.

The lower furnace-head shown by way of example in Fig. 2 can, depending on circumstances serve for the taking off of the metal, for the re-

moval of residues, for the supply of heating medium, etc., or simultaneously for several of such purposes or all of them. The metal flows continuously, for example through the openings 19 5 pierced through a number of places in the lower end wall 19a, into the duct 20 in the furnace-head, and which removes the metal by siphon action. If residues or slags are present which float on the metal, they can be brought out 10 through the pipe 21 into the down-pipe 22, through which they reach the bunker 26. On the down-pipe 22 is placed the bell or cover 23, having a water trough 24 which forms a gas tight seal between the bunker and the open air. The 15 bunker 26 can be emptied by opening the sliding gate 25.

The supply of heating medium to the fire ducts of the muffle may be received through the pipe 27 into the annular space 30, which is closed off from 20 the furnace by the sliding surfaces or labyrinths 28, 29 shown in Figure 10, and is connected with the fire ducts 18. The combustion air is brought into the fire ducts by way of the damper-adjustable air nozzles 31. The muffle in all its various 25 possible embodiments can also lie horizontally. In particular, when so arranged, it can be operated by charges. The gas outlets can also be located at other points of the muffle or of the fire ducts, or even of the upper directly heated 30 portion of the furnace. If the closure 41 in Figure 9 be opened, then gas will flow out of the muffle at this point. In this way for example, a continuous operation of the muffle is possible. The muffle cross-section can be circular, oval, angular, 35 or of other shape. This cross-section can be different at different points of its length.

The muffle furnace according to the present invention has an exceedingly manifold field of application. For example it is suitable for the 40 melting out of metals from ashes, drosses, and other materials containing metals together with impurities; for the reduction of oxides to metal with indirect and combined indirect and direct heating; for the calcination and drying of materials which cannot be allowed to come into contact with heating gases at any but low temperatures, if at all; for the volatilization of elements, e. g., metals, or of oxides and other compounds; for the effecting of chemical reactions, 45 such for example as chlorination and the volatilization of chlorides; and for other like uses.

I claim:

1. Rotary muffle furnace comprising a muffle to receive the material to be treated and a shell 55 carrying said muffle, said furnace being heated during rotation by fire ducts disposed between the muffle and the shell, and radially yielding parts associated with said shell and muffle for directly connecting said muffle to said shell.

2. Rotary muffle furnace comprising a muffle to receive the material to be treated and a shell having counter bearings, said furnace being heated during rotation by fire ducts disposed between the muffle and the shell, and radially yieldable parts pressing said muffle against the counter 60 bearings.

3. Rotary muffle furnace comprising a muffle and a masonry shell having inwardly projecting bricks forming bearings for said muffle, and 70 radially spring pressed plungers carried by said shell urging said muffle against said bearings.

4. Rotary muffle furnace comprising a muffle and a masonry shell having inwardly projecting portions, and spring pressed plungers carried by 75 said shell for urging said muffle radially against

said inwardly projecting portions, said plungers and said portions having bearing parts, and shoes interposed between said muffle and certain of said bearing parts.

5. Rotary muffle furnace comprising a muffle and a masonry shell having inwardly projecting bricks forming bearings for said muffle, shoes engaging said muffle and carried by pairs of bricks, and plungers mounted between said pairs of bricks and radially spring pressed against said 10 shoes.

6. Rotary muffle furnace comprising a muffle and a shell having counter bearings, said muffle consisting of joined sections, and spring pressed plungers carried by said shell and urging said 15 muffle radially against said counter bearings and resiliently holding the joints together.

7. Rotary muffle furnace comprising a muffle and a shell having counter bearings, said muffle consisting of joined sections having inwardly directed annular projections, and resilient means carried by said shell urging said muffle against 20 said counter bearings.

8. Rotary muffle furnace comprising a muffle and a shell having counter bearings, said muffle 25 consisting of sections having interfitting joint surfaces, and resilient means carried by said shell radially urging said muffle against said counter bearings and thereby tightening said joints.

9. Rotary muffle furnace comprising a muffle and a shell having counter bearings, and spring 30 pressed plungers carried by said shell urging said muffle against said counter bearings, said muffle having inwardly directed annular projections interrupted at points where the muffle rests on said 35 counter bearings.

10. Rotary muffle furnace comprising a muffle and a shell having counter bearings, and yieldable means pressing said muffle against said 40 counter bearings, the inner surface of said shell, the outer surface of said muffle, and the lateral surfaces of said counter bearings defining fire ducts for said furnace.

11. Rotary muffle furnace comprising a muffle having longitudinal ribs, and a shell having 45 counter bearings, and spring pressed plungers carried by said shell and urging said muffle against said counter bearings.

12. Rotary muffle furnace comprising a muffle constructed of heat and corrosion resisting metal, 50 a shell having a refractory lining with inwardly projecting portions forming counter bearings, and radially yieldable means carried by said shell pressing said muffle against said counter bearings.

13. Rotary furnace comprising a muffle and a shell having a lining and counter bearings, and yieldable means pressing said muffle against said 55 counter bearings, the inner lining of said shell, the outer surface of said muffle, and the lateral surfaces of said counter bearings defining fire 60 ducts, said furnace having a part constructed and arranged for direct heating and connected to said muffle, and means for passing heating medium into the interior of said furnace between said fire ducts and said part constructed and arranged 65 for direct heating and connected to said muffle.

14. Rotary furnace comprising a muffle and a shell having counter bearings, and yieldable means pressing said muffle against said counter 70 bearings, the inner surface of said shell and the outer surface of said muffle and said counter bearings defining fire ducts, said furnace having a part constructed and arranged for direct heating and connected to said muffle, means for supplying heating medium to said fire ducts at one 75

end of said furnace, and means for supplying combustion air at points distributed along the length of the ducts.

15. Rotary furnace comprising a muffle and a shell having counter bearings, and means pressing said muffle against said counter bearings, said

furnace have a part constructed and arranged for direct heating and connected to said muffle, said furnace having separated outlets for the removal of solid, liquid and gaseous substances.

PAUL JORDAN.
